UNITED STATES PATENT OFFICE

JULIUS A. SCHWANTES, OF WAUWATOSA, WISCONSIN, ASSIGNOR TO COLGATE-PALM-OLIVE-PEET COMPANY, OF CHICAGO, ILLINOIS, A CORPORATION OF DELAWARE

APPARATUS FOR TREATING SOAP

Application filed March 13, 1931. Serial No. 522,319.

The invention relates to apparatus for forming markings in soap.

It is usual in the manufacture of soap to impress by either taglio or intaglio impression, distinctive markings, such as names or designs on the face or faces of the soap cake. These markings soon wear off after the soap cake has been in use for a brief period.

The object of the present invention is to provide an apparatus for forming a cavity or cavities in the soap cake conforming to the distinctive marking to be displayed and the filling of the cavity or the cavities with a filler substance, such as soap having a different characteristic or grain from that of the remainder of the cake, which will wear down as the cake is used up and wherein the soap cake may be treated by automatically operating mechanism to form the cavity or cavities and insert the filler substance therein accurately and expeditiously. More particularly, the various operations to which the soap is subjected are carried out while the soap is moving on a rotary conveyor and the finished cake delivered within a single revolution of the conveyor.

The invention further consists in the several features hereinafter set forth and more particularly defined by claims at the conclusion hereof.

In the drawings, Fig. 1 is a side elevation view of an apparatus embodying the invention, parts being broken away and parts being shown in section,

Referring to the drawings, and to Figs. 1 and 15, a general description of certain of the parts and cycle of operations of the apparatus will first be given for a more ready understanding of the invention. In these figures, the numeral 24 designates an intermittently rotated rotary conveyor or carrier having cavities 25 formed therein and providing stations A, B, C, D, E, F, G, H. At the station A, the soap to be treated is introduced either in the form of a previously formed cake or as hereinafter described formed into a cake S. Between the stations A and D, the carrier runs over a backing or bottom plate 26. Stations B, F and H are dwell stations. At station C the soap cake S is subjected to the action of a die or dies I formed of one or more parts having a configuration of the character of the distinctive marking it is desired to have appear in the soap and for this purpose the parts of the

die may be formed in letters, characters, symbols or designs. At this station, the die is forced into the cake of soap to form one or more cavities J therein, the cavities in the 5 soap shown in the drawings being made in accordance with the configuration of the die which, for example, in the present instance is formed to provide impressions corresponding to the letters O. K., the die parts being so 10 formed as shown in Fig. 16. At station D, a filler substance J' such as soap having the same or a different characteristic from that of the cake and which has been previously delivered from a hopper L to a female die member M having a slot or slots 27 formed therein corresponding in outline to the configuration of the die or dies I and hence the cavity or cavities previously formed in the soap cake, said filler is forced from said die member M 15 20 into the cavity or cavities J in the soap cake by a die or dies N similar to the die I. At station E the soap may be acted upon by a pair of finishing dies P and R and at station G the finished cake is discharged from 25 the carrier onto a delivery conveyor T.

Referring to Figs. 1, 2 and 3, the numeral 28 designates generally the main framework of the machine supported on suitable legs or uprights 28' and 29, the main power take-off 30 shaft journalled in bearings 29' suitably supported by rods 30 below the main frame and carrying sprockets 31, 32, and 33. The sprocket 31 is adapted to be connected by a chain 34 to any suitable source of power. 35 Sprocket 32 is connected by a chain 35 to a sprocket 36 on one of the parts of a lay shaft 37 and sprocket 33 is connected by a chain 38 to a sprocket 39 on a shaft 40. The shaft 37 is connected by a double chain and 40 sprocket drive including sprockets 41 on said shaft, chains 42 and sprockets 43 on a shaft 44 to said last named shaft. A Geneva toothed gearing connects the shaft 44 with a shaft 45 carrying a gear 46 meshing with 45 a gear 47 mounted on a carrier drive shaft 48. The shaft 37 is journalled in suitable bearing brackets 37' mounted on the main frame, the shafts 44 and 45 are journalled in suitable bearings provided in the spaced brackets 38' and 39' while the shaft 48 is journalled in roller bearings 40' mounted in a housing 41' suitably secured to the brackets 38' and 39'. The Geneva stop gearing as 50 shown in detail in Fig. 12 includes the Geneva toothed wheel 42' on the shaft 45 having the tooth slots 43' engaged by the pin or roller 44' on the arm 45' secured to the shaft 44 and having lock recesses 46' cooperating with the lock disk 47' on the shaft 44 whereby as the shaft 44 is rotated continuously, the shaft 45 is given an intermittent or step by step rotation which is transmitted through the gears 46 and 47 to the carrier shaft 48.

The carrier 24 is in the form of a drum 60 bolted to the flanged end of the shaft 48 and

the cavities 25 are formed in the flange of the drum at radially spaced points and are preferably provided with hard metal linings 25', see Fig. 3.

The backing plate 26 is, as shown in Figs. 3 70 and 4 shaped to conform to the inner cylindrical face of the drum or carrier 24 and is of T section with its flange secured to a relatively stationary angle bracket 26', which however is mounted for movement as herein-after described along with other parts of the mechanism to withdraw the plate 26 from the interior of the carrier when desired.

It has been pointed out that at station A of the carrier either a previously formed soap cake may be deposited in the cavity 25 then presented on the cake may be formed therein and mechanism has been here shown for the latter purpose and is shown in Figs. 1, 2 and 4 wherein the numeral 49 designates an outlet conduit or nozzle designed for attachment or use in conjunction with a suitable plodder mechanism and into which nozzle the soap is forced by the feed screw or screws of the plodder under pressure. As the soap is forced through this nozzle 49 it is acted upon by a pair of pusher cams 50 mounted on oscillatory shafts 51 carrying intermeshing gears 52 and one of the shafts being oscillated by its adjustable connection 95 through a crank arm 53 on it to one end of a connecting rod 54 operatively and adjustably connected at 55 to one of a series of radially spaced pin receiving openings 56 in a crank disk 57, on the shaft 40. The pusher members or cams 50 are for the purpose of quickly forcing the soap ahead at the time the carrier 24 is at rest and when receding they stop the movement of the soap at outlet of the plodder nozzle at the time the carrier is in motion. 100 The front end of the nozzle 49 is formed by a jacketed chamber 58 through the jacket 59 of which a suitable heating medium may be circulated. A nozzle member 60 is adapted to fit within the recessed end of nozzle 49 and 105 its front face 60' is curved to conform to the curvature of the carrier with the result that after the cavity 25 presented to it has been filled with soap and the carrier revolves to its next position the soap in the cavity is cut off from the soap in the nozzle 49 by the interaction of these interfitting surfaces. The member 60 is yieldingly held against the carrier by a series of springs 61 mounted in recesses 62' and engaging lugs 63' on the member 60, one of the springs being shown in Fig. 23.

This method and apparatus for forming a soap cake in a single operation directly at the discharge of the plodder is in itself new and 125 is being made the subject matter of a separate application as it may be used irrespective of the marking of the soap as hereinafter described though it is also of great advantage in the present combination.

It has been noted that when the soap cake reaches the position C, the die I is moved to make the cavity or cavities in the cake. For this purpose the die I is secured to the lower 5 reduced end of sliding rod 61 here shown as of square section mounted to slide in stationary guides 62, said rod having a rack 63 formed in it meshing with a gear 64 on a shaft 65 journaled in bearings on a bracket 10 66 also forming part of the guides 62, see Figs. 2 and 4. At its outer end, the shaft 65' carries a crank arm 67 pivotally connected to a cam actuated rod 68, shown in detail in Fig. 11, having a forked lowered end 69 working over a bushing on the shaft 44 and carrying a roller 70 working in a grooved cam 71 on said shaft, this drive mechanism being timed to impart a single reciprocation to the die I as each soap cake is at rest under it. 15

20 A stripper plate 72 having openings 72' therein conforming to the configuration of the male die I is yieldingly supported in position adjacent the face of the carrier by rods 73 slidably mounted in guides 74 on the plunger or rod 61 and urged outwardly by springs 75, the die I moving relatively to said plate 72 and into the soap cake to provide the cavity or cavities in the cake to a depth of about half the thickness of the cake. 25

30 The hopper L has integrally formed side 76 and front end 77 connected by an angled extension 78 and bolts 79 to the bracket 39' and the die M is mounted in a movable bottom plate 80 whose lower surface is curved to conform to the curvature of the carrier as shown in Fig. 4 and the front end of the hopper is formed by a fixed plate 81, it being noted that the bottom plate 80 is free to oscillate between the carrier and the lower edges of the ends 77 35 and 81 of the hopper and between the sides 76 thereof and has a stepped front end portion 80' to assist in agitating the contents of the hopper. The bottom plate 80 is bolted to a portion of a ring shaped member 82 as shown in Fig. 5 and this member 82 is in itself 40 mounted to turn or oscillate in an annular bearing element 83 secured by bolts 83' to the housing 41'. Outside of the hopper the bottom member or plate 80 has a bracket or arm 84 secured to it and carrying a cam roller 85 working in a grooved cam 86 on the shaft 44 see Figs. 2 and 4 which acts to oscillate the bottom plate during the time the carrier is moving the cake from station C to station D. 45

50 As the filler substance such as soap in either chip, flake, granular, powdered or other form may not feed itself into the cavity or cavities formed by the slot 27 in the female die M, means have been provided for agitating the contents of the hopper and also exerting a feeding action into the die which are shown in Figs. 4, 7 and 18 to 20. It includes a pusher plate 87 mounted to slide between the sides of the hopper guides 87' and plate 81 and having 55 a serrated face 88. A rack bar 89 is mounted in the upper recessed end of the plate 87 and is secured thereto for movement with and relative to said plate by a screw bolt 90 anchored to the plate and working in a slot 91 in the lower end of the rack and cooperating with a channel plate 92 to hold the rack in proper position, said bar having a cylindrical extension 89' working through a lug 93 on the plate 87. A spring 94 is interposed between the lug 93 and nuts 95 on said extension and 60 normally holds the rack bar in an upper position though if too much resistance is encountered by the plate 87 on the downward movement of the rack, said rack may move relative to said plate under the action of said spring. The rack 89 meshes with a segmental rack gear 96 mounted on a shaft 97, as shown in Fig. 1, carries a crank arm 98 operatively connected by link 99 with a crank arm 100 on a shaft 101 which, as shown in Fig. 10 carries a crank arm 102 provided with a roller 103 working in a grooved cam 104 from which the rack receives its reciprocatory movement during the time the carrier is advancing from station to station, said cam being mounted on the shaft 44. Referring to Figs. 18 to 20, it will be noted that the lower end of the plate 87 has a pusher foot 105 mounted thereon for yielding relative movement thereto. The central portion 106 of this foot has a relatively sharp edge to assist in forcing the filler into the die and end portions provided with post extensions 107 slidably mounted in bores or slots 108 formed in the lower end of the plate 87 and engaged by springs 109 also mounted in said bores between the upper ends thereof and the tops of said posts, said posts being prevented from any tendency toward rotation by cross pins 110 working in slots 111 in said plate. The lower end of the plate 87 is recessed to receive the post 105 which is slidably mounted between said plate and a back guide plate 112 secured to the plate 87 by screws 113. With the above construction, if the pusher foot encounters too much resistance in its downward movement with the plate 87 it may yield relative to the plate 87 under the action of the springs 109 and during its downward movement said foot works in the space in the hopper between the plate 81 and the stopped position 80 of the bottom plate, it being noted that by stopping this part of the plate the filler substance will be trapped sufficiently so that the pusher foot 105 will be sure to have sufficient material to act up to force into the die M which has then moved to a position under said foot. Thus the movable die M is filled with the inserting material and then moves back to the position shown in Fig. 4 as the next cake of soap comes to its station D and then this filler substance is forced from the die M by the male die N into the previously formed cavity or cavities in the soap cake. 120

125 Referring to Figs. 4 and 7, the die N is secured to a slide plate 114 which is slidably

mounted in grooved ways 115 formed in the end plate 81 of the hopper and a removable gib 116. This slide plate is, similar to the plate 87, mounted for movement with and relative to a rack bar 117 which is connected by a bolt 118 and slot 119 in a manner similar to the rack bar 89. This bar 117 has a cylindrical extension 120 working through a lug 121 on the plate 117 and surrounded by a spring 122 interposed between said lug and stop nuts 123 on said extension and is in mesh with a rack gear 124 mounted on a shaft 125, which as shown in Fig. 10, is provided with a crank arm 126 carrying a roller 127 working in the grooved cam 104 and timed to reciprocate bar 117, plate 114 and die N while the soap cake is at rest at station D.

In order to polish and put a final finish on the soap cake, the next movement of the carrier brings the cake into the position between the oppositely disposed dies P and R which are secured to the heads of plungers 128 and 129 that are operated by drive eccentrics or cranks from the shaft 37.

Referring to Figs. 2, 3, 4 and 13, the plunger 128 has squared portions 128' slidably guided in relatively fixed guides 130 and secured by a clamping boss 131 on a block 132 to which a shaft or rod 133 is firmly secured. This shaft 133 is slidably mounted in relatively fixed bearing brackets 134 and is pivotally connected by a pin 135 to the forked end 136 of a rod 137 which is mounted in a guide 138 of a cap member 139 and has a headed end engaged by a spring 140 seated in said cap member which is secured to the big end bearing or eccentric strap 141 by bolts 142, said strap having a roller bearing journal 143 mounted on a crank or eccentric 144 formed on a part of the shaft 37. This construction thus provides a reciprocating drive movement for the die P, the spring 140 permitting a predetermined pressure to be impressed by the die on the soap cake. The drive for the plunger 129 is similar and such features as differ are shown in Figs. 2, 4 and 14 wherein it will be noted that the plunger 129 has a squared portion 129' working in a relatively fixed guide 145 and provided with a pivot pin 146 connected to the forked end of a rod 147 which is slidably mounted in a guide 148 secured to the eccentric strap 149 and is yieldingly connected thereto by a spring 150 interposed between a flange 147' on said rod and said strap, the rod and spring being operatively held in position by a cap member 151 secured to said strap, this strap or big end bearing of the yieldable connecting rod thus formed having a journal bearing similar to the journal 143 and mounted on another crank portion 152 of the shaft 37 to act to force the die R inwardly and through the spring 150 impart a predetermined pressure to the cake, the dies P and R

acting conjointly under the action of their springs and drive for this purpose.

As the dies P and R may be of different contours for different sides of the cake, they are as shown in Figs. 8 and 9 attached to their plunger heads in different ways, it being noted that the slots 152 for the bolts 153 securing the die R to its plunger are different than the slots 154 for the bolts 155 securing the die P to its plunger. 75

The soap cake is now finished ready to be discharged from the machine and conveyed by the conveyor T to the wrapping mechanism. For discharging the finished cake from the carrier a push out plunger 156 is mounted to reciprocate at the discharge station G into and out of the cavity 25. Said plunger as shown in Fig. 4 is carried by a crank arm 157 on a shaft 158 and steadied by a pivotally supported guide link 159, the shaft 158 as shown in Fig. 1 carrying a crank arm 160 operatively connected to an eccentric or crank 161 on the shaft 37 by a long connecting rod 162. 80

It has been previously noted that it is desirable to gain access to the interior of the carrier at times as for example when the machine is being first charged, and consequently the supporting bracket 26' for the plate 26 is mounted on a bracket 163 which carries the bearings for the shaft 128, and 95 133, the shaft 158 and which is secured to a movable bed plate 164 which also carries the bearings 37' for the front section of the shaft 37, said shaft being divided into sections as shown in Fig. 2 by the toothed coupling members 165 so that it may be separated at this point when the bed plate 164 is moved forward. For moving said bed plate, it is provided on its bottom with suitable 100 racks 166, not shown in detail, meshing with spaced gears 166' in a manually operated shaft 167 journalled in the main framework of the machine and provided with a hand wheel 168 and for realining the parts of the 110 coupling members 165, the other shaft section is provided with a hand wheel 169. 105

It will also be noted from Figs. 4 to 6 that the female die member M is removably inset in the bottom plate member 80 and secured 115 therein by screws 170.

As a general description of the method of operation of the apparatus and a detailed description of each of the operating mechanisms acting in conjunction with the carrier 120 to perform the desired operations of the soap cake have been given further description is deemed unnecessary. Fig. 21 shows a perspective view of the finished soap cake in which the distinctive marking appears therein by the plastic insert material J' that has been inserted into the cavities J formed by the die member I. 125

I desire it to be understood that this invention is not to be limited to any particular 130

form or arrangement of parts except in so far as such limitations are included in the claims.

What I claim as my invention is:

5. In an apparatus of the character described, the combination of a movable carrier, means for forming a cavity or cavities of the desired configuration in a body of soap on said carrier in one position of said carrier, and means for filling said cavity or cavities with a filler substance in another position of said carrier. 70
10. In an apparatus of the character described, the combination of a reciprocatory die for forming a cavity or cavities of the desired configuration in a body of soap, a member provided with a cavity or cavities conforming to the configuration of said first named die, means for filling the cavity or cavities of said member with a filler substance, means for forcing said filler substance from the cavity or cavities of said member into the previously formed cavity or cavities in the body of soap and means for moving said soap from a cavity forming position to a cavity filling position. 75
15. In an apparatus of the character described, the combination of means for forming a cavity or cavities of the desired configuration in a body of soap, a movable member provided with a cavity or cavities conforming to those previously made in the soap, means for charging the cavity or cavities of said member with a filler substance, means for forcing said filler substance from the cavity or cavities of said member into the cavity or cavities previously formed in the soap, and means for progressively moving the soap to a cavity forming position and thence to a cavity filling position. 80
20. In an apparatus of the character described, the combination of means for forming a cavity or cavities of the desired configuration in a body of soap, a hopper for a filler substance, a member provided with a cavity or cavities conforming to those previously made in the soap and movable to a position to receive the filler substance from the hopper, means in said hopper for forcing said filler substance into the cavity or cavities in said member, means for forcing said filler substance from the cavity or cavities of said member into the cavity or cavities previously formed in the soap, and means for moving the soap to a cavity-forming position and thence to a cavity-filling position. 85
25. In an apparatus of the character described, the combination of an intermittently movable rotary carrier provided with soap receiving cavities, means for successively charging said cavities with soap to form soap cakes therein, means for forming a cavity in each soap cake while on the carrier, means for inserting a filler substance into the cavities in the soap cakes while on the carrier, and means for successively discharging the soap cakes from the carrier. 90
30. In an apparatus of the character described, the combination of an intermittently movable rotary carrier provided with soap receiving cavities, means for successively charging said cavities with soap to form soap cakes therein, means for forming a cavity in each soap cake while on the carrier, means for inserting a filler substance into the cavities in the soap cakes while on the carrier, a pair of oppositely movable finishing dies for pressing the soap cakes on the carrier between them, and means for successively discharging the pressed soap cakes from said carrier. 95
35. In an apparatus of the character described, the combination of a rotary carrier provided with soap receiving cavities, means for forming a cavity in the soap in said cavities, means for filling said cavities in the soap, means for putting a finish on the soap while in the carrier, means for discharging the finished soap from the carrier, and means for carrying the finished soap away from the apparatus. 100
40. In an apparatus of the character described, the combination of a rotatable cylindrical carrier provided with soap receiving cavities, a movable die for forming cavities in the soap in the carrier, a hopper for a filling substance, a movable bottom for said hopper mounted to oscillate over a portion of the carrier and provided with a female die conforming in outline to said first named die, means in the hopper for charging said female die with said filling substance, and male die for forcing the filler substance in the female die into the cavities previously formed in the soap. 105
45. In an apparatus of the character described, the combination of a rotatable cylindrical carrier provided with soap receiving cavities, a reciprocatory die for forming cavities in the soap in the carrier, a hopper for a filler substance, a movable bottom for said hopper mounted to oscillate over a portion of said carrier and provided with a female die conforming in outline to said first named die, a reciprocatory pusher member in said hopper for forcing said filler substance into said female die, and reciprocatory male die for forcing the filler substance in the female die into the cavities previously formed in the soap. 110
50. In an apparatus of the character described, the combination of a movable carrier provided with soap receiving cavities, a reciprocatory die for forming cavities in the soap in the carrier, a hopper for a filler substance, a movable bottom for said hopper mounted over a portion of said carrier and provided with a female die portion conforming in outline to said first named die, multi-pact reciprocatory pusher member in said hopper for forcing said filler substance into 115
55. In an apparatus of the character described, the combination of a movable carrier provided with soap receiving cavities, a reciprocatory die for forming cavities in the soap in the carrier, a hopper for a filler substance, a movable bottom for said hopper mounted over a portion of said carrier and provided with a female die portion conforming in outline to said first named die, multi-pact reciprocatory pusher member in said hopper for forcing said filler substance into 120
60. In an apparatus of the character described, the combination of a movable carrier provided with soap receiving cavities, a reciprocatory die for forming cavities in the soap in the carrier, a hopper for a filler substance, a movable bottom for said hopper mounted over a portion of said carrier and provided with a female die portion conforming in outline to said first named die, multi-pact reciprocatory pusher member in said hopper for forcing said filler substance into 125
65. In an apparatus of the character described, the combination of a movable carrier provided with soap receiving cavities, a reciprocatory die for forming cavities in the soap in the carrier, a hopper for a filler substance, a movable bottom for said hopper mounted over a portion of said carrier and provided with a female die portion conforming in outline to said first named die, multi-pact reciprocatory pusher member in said hopper for forcing said filler substance into 130

said female die, the parts of said pusher member being yieldingly connected together for movement relative to each other, and a reciprocatory male die for forcing the filler substance in said female die into the cavities previously formed in the soap.

11. In an apparatus of the character described, the combination of a movable carrier provided with soap receiving cavities, a reciprocatory die for forming cavities in the soap in the carrier, a hopper for a filler substance, a movable bottom for said hopper mounted over a portion of said carrier and provided with a female die portion conforming in outline to said first named die, a pusher member in said hopper for forcing said filler substance into said female die, means including a yieldable drive connection for reciprocating said pusher member, and a reciprocatory male die for forcing the filler substance in said female die into the cavities previously formed in the soap.

12. In an apparatus of the character described, the combination of a removable carrier provided with soap receiving cavities, a reciprocatory die for forming cavities in the soap in the carrier, a hopper for a filler substance, a movable bottom for said hopper mounted over a portion of said carrier and provided with a female die portion conforming in outline to said first named die, a reciprocatory pusher member in said hopper for forcing said filler substance into said female die, a male die for forcing the filler substance in said female die into the cavities previously formed in the soap, and means including a yieldable drive connection for reciprocating said last named male die.

13. In an apparatus of the character described, the combination of a rotatable cylindrical carrier provided with soap receiving cavities, a reciprocatory die for forming cavities in the soap in the carrier, a hopper for a filler substance, a movable bottom for said hopper mounted to oscillate over a portion of said carrier and provided with openings conforming to the configuration of said first named die, reciprocatory pusher member mounted in said hopper to force the filler substance into said openings, and a reciprocatory die mounted outside of said hopper.

14. In an apparatus of the character described, the combination of a rotatable drum having soap receiving openings in its periphery, means for intermittently rotating said drum, a backing portion unlying a portion of the periphery of said drum, means for forming a cavity of the desired configuration in the soap in said openings while the drum is passing over said backing member, means for inserting a filler substance into the cavity thus formed in the soap while the drum is passing over said backing member, and

means for withdrawing said backing member from said drum.

15. In an apparatus of the character described, the combination of an intermittently rotatable carrier provided with soap receiving cavities, means for forcing soap into said cavities to form cakes, means for forming cavities in said cakes, means for filling said cavities with a filler substance, means for pressing on opposite sides of the soap cakes while in the carrier to impart a finish thereto, and means for pushing the finished cakes out of the cavities in the carrier.

In testimony whereof, I affix my signature.
